GLASGOW, SCOTLAND

HEAT EXCHANGE APPARATUS FOR HEATING OR COOLING FLUIDS

Application filed December 14, 1931, Serial No. 580,974, and in Great Britain June 23, 1931.

This invention has reference to improvements in heat exchange apparatus for heating or cooling fluids and has for an object the provision of a heat exchanger for fluids (liquid and/or gaseous) in which two fluids flow in relatively thin, flat, parallel streams, either in the same or in opposite directions, and are separated by thin flat walls.

A heat exchanger, according to the invention, comprises two sets of relatively deep, narrow and long channels or shallow, broad and long channels, arranged with the channels of the one set alternating with the channels of the other set. An inlet is provided at one end of each set of channels and an outlet is provided at the other end of each set of channels so that the fluids flow longitudinally through the channels in thin flat streams. The inlets to the sets of channels may be at the same end of the exchange apparatus so that the fluids flow in parallel streams in the same direction or alternatively the inlets to the sets of channels may be at the opposite ends of the apparatus so that the fluids flow in parallel streams in opposite directions.

The channels may be formed by cutting in opposite faces or surfaces of a metal plate a plurality of grooves, the one set of channels being formed in one surface of the plate and the other set of channels being formed in the opposite surface of the plate so that the channels on opposite surfaces alternate with each other.

In the accompanying drawings Fig. 1 is a sectional elevation and Fig. 2 is an elevation at right angles thereto illustrating one embodiment of heat exchange apparatus in accordance with this invention. Fig. 3 is a face view or elevation, Fig. 4 is a sectional elevation at right angles thereto and Fig. 5 is a sectional plan view of the grooved plate illustrated by Figs. 1 and 2. Figs. 6, 7 and 8 are views similar to Figs. 3, 4 and 5 but illustrate a modified construction. Fig. 9 is a face view or elevation and Figs. 10 and 11 are sectional elevations taken, respectively, on the lines 10-10 and 11-11 of Fig. 9 of the outer plate for use in the modification illustrated by Figs. 6 to 8. Fig. 12 is an eleva-

tion, partly in section and Fig. 13 is a plan view, also partly in section, illustrating a further embodiment or modification. Figs. 14 and 15 are fragmentary sectional elevations of modified constructions of the grooved plate and Fig. 16 is a sectional elevation illustrating a modified formation of the grooves in the grooved plate.

According to one embodiment of the invention, illustrated by Figs. 1 to 5 which is adapted, particularly for use as an oil heater, a plurality of relatively deep and narrow grooves 1, 2 are formed in each surface of a metal plate 3, which, desirably, is arranged with the grooves vertical. The grooves 1 cut in one surface of the plate 3 alternate with the grooves 2 cut in the other surface and the walls 4 which separate the grooves 1 and 2 are relatively thin. The grooved plate 3 is sandwiched between two outer plates 5 and 6 which may be covered with heat retaining material 7, the three plates 5, 3 and 6 being secured together by bolts. The grooves 1 and 2, preferably, do not extend to the top and bottom edges of the plate 3 and are covered by the outer plates 5 and 6. At the upper end of the plate 6 a steam inlet 8 is provided and at the lower end of said plate 6 a steam or drain outlet 9 is provided. At the lower end of the plate 5 an oil inlet 10 is provided and at the upper end of said other outer plate 5 an oil outlet 11 is provided. Steam flows in thin parallel streams longitudinally down the grooves 2 in the plate 3 and oil flows in thin parallel streams longitudinally up the grooves 1 in the plate 3, the steam streams alternating with the oil streams and, desirably, the outer streams being steam streams.

According to a modified construction the grooves, instead of being covered by outer plates may be covered by filling pieces welded or otherwise fitted into the grooves.

The fluids or one of the fluids may flow through the apparatus in one or more passes.

As illustrated by Figs. 6 to 11 the grooves 2 may be covered, for the major portion of their length, by filling pieces 12 welded or otherwise fitted into the grooves. A block 13 divided into two compartments 14 and 15

by a partition 16 may be welded or otherwise secured to the plate 3 so as to cover the one ends of the grooves 2 and another block 17 having a chamber 18 may be welded or otherwise secured to the plate 3 so as to cover the other ends of the grooves 2. The compartment 14 is provided with a steam inlet connection 19 and is open to the one half of the grooves 2 and the compartment 15 is provided with a steam outlet 20 and is open to the other half of the grooves 2. The chamber 18 is open to all the grooves.

In this arrangement the steam or other fluid enters the compartment 14 through the inlet connection 19, flows through one half of the grooves 2 to the chamber 18, then flows from said chamber 18 through the other half of the grooves 2 to the compartment 15 and is discharged through the outlet connection 20, the steam or other fluid flowing through the apparatus in two passes.

The oil or other fluid may flow through the grooves 1 in the plate 3 in several passes. As illustrated (Fig. 9) the plate 5 at one end is formed with a plurality of pockets 21 and 22 and at the other end with a plurality of pockets 23 and 24.

In the construction illustrated the pocket 21 extends over the ends of three grooves 1 so that oil flows from the inlet connection 10 through the first three grooves 1 in parallel to the pocket 23 which extends over four grooves. The oil then flows through the other grooves 1 in series, the pockets 22 and 24 each extending over two grooves 1, to the outlet connection 11.

According to the modification illustrated by Figs. 12 and 13, which is particularly suitable for use as an oil cooler, two plates 3, each provided with alternating grooves as shown by Figs. 5 and 8, are arranged spaced apart with a casting 25 sandwiched therebetween. The centre portion of the casting 25 covers the major portion of the grooves 1, the ends of the grooves opening into chambers 26 and 27 formed at each end of the casting 25. The chamber 26 is provided with an inlet connection 28 and the chamber 27 is provided with an outlet connection 29. The ends of the casting 25 are similarly constructed.

Water or other cooling (or heating) medium enters chamber 26 through the connection 28 and flows through the grooves 1 to the chamber 27 where it is discharged through the connection 29.

On the outer sides of the plates 3 castings 30 and 31 are arranged, the castings 30, 31, plates 3 and casting 25 being bolted together. The centre portions of the castings 30 and 31 cover the major portions of the grooves 2 in the plates 3. At one end the casting 30 is provided with a chamber 32 open to the ends of all the grooves 2 of the adjacent plate 3 and the other end of the casting 30 is provided with two compartments 33 and 34

separated from each other by a division wall 35. The lower compartment 33 is provided with an inlet connection 36 and the upper compartment 34 is provided with an outlet connection 37. The casting 31 is similar to the casting 30 the lower compartment, corresponding to the compartment 33, being provided with a discharge outlet 38 and the upper compartment, corresponding to the compartment 34 being provided with an inlet branch 39 which is connected to the outlet connection 37 by a pipe 40 which bridges the apparatus and is indicated by dotted lines (Fig. 13).

Oil enters the compartment 33 through the inlet connection 36, flows through the lower grooves 2 of the adjacent plate 3 to the chamber 32 and from said chamber flows through the upper grooves 2 of said plate 3 to the compartment 34. From said compartment 34 the oil flows by way of the outlet connection 37, pipe 40 and inlet branch 39 to the upper compartment of casting 31 corresponding to compartment 34 of casting 30, then through the upper grooves 2 of plate 3 associated with casting 31 to the end chamber or casting 31, then through the lower grooves 2 to the lower compartment of casting 31 and is discharged through discharge outlet 38.

In cases where the depth of the grooves 1, 2, is such that it is desirable to stiffen or strengthen the side walls 4 of the groove a tube or stay 41 (Fig. 14) may be passed through these walls and expanded into the tube holes formed in the walls. Alternatively and as shown by Fig. 15 a portion of alternate grooves may be cut from one side of the plate and the remaining portion of said grooves cut from the other side of the plate so that an uncut portion 42, constituting a stiffener, may be left in the intermediate portion of the grooves. This uncut portion may be perforated as indicated by dotted lines 43 to provide a passage for the fluid from one portion of the groove to the other and the grooves may be closed by filling pieces 12 welded or otherwise secured therein.

If desired retarders, which may be serrated, may be fitted in one or in both sets of grooves. These retarders may act as stiffeners for the walls of the grooves and the grooves may be of different dimensions.

According to the modification illustrated by Fig. 16 the grooves 1 and 2 may be formed somewhat of V-shape and the grooves on one side of the plate 3 may be filled in with filling pieces 12 which extend for the major portion of the grooves intermediate the ends thereof.

What we claim is:—

1. A heat exchange apparatus for heating or cooling fluids comprising two sets of straight channels cut in opposite faces or surfaces of a metal plate with the ends of the channels spaced from the ends of the plate

so that the channels of one set alternate with the channels of the other set and means whereby a fluid is caused to flow through each set of channels in one or more passes.

5 2. A heat exchange apparatus as claimed in claim 1 in which the plate having the grooves cut in opposite faces is sandwiched between plate members or castings each of which is provided at one end with an inlet 10 chamber and at the other end with an outlet chamber.

3. A heat exchange apparatus as claimed in claim 1 in which the plate having the grooves cut in opposite faces is sandwiched 15 between plate members or castings having at the end thereof chambers which extend over the ends of all the grooves in the adjacent face of the plate whereby the fluids flow through the grooves in one pass.

20 4. A heat exchange apparatus as claimed in claim 1 in which the plate having the grooves cut in opposite faces is sandwiched between plate members or castings having at the ends thereof one or more chambers divided into 25 compartments by division walls whereby one or both fluids may flow through the grooves in a plurality of passes.

5. A heat exchange apparatus as claimed in claim 1 in which the grooves of a set of 30 grooves are closed intermediate their ends by filling strips and the ends of the grooves are left open.

6. A heat exchange apparatus as claimed in claim 1 in which the ends of the grooves 35 are open to pockets formed in an outer plate, placed against the grooved face of the grooved plate whereby one of the fluids may flow through some of the grooves in parallel and the remainder of the grooves in series.

40 7. A heat exchange apparatus as claimed in claim 1 in which two plates grooved in opposite faces are spaced apart with a casting sandwiched therebetween and provided with inlet and outlet chambers whereby a fluid may 45 flow from said inlet chamber through the grooves in adjacent faces of the grooved plates to the outlet chamber.

8. A heat exchange apparatus as claimed in claim 1 in which two plates grooved in opposite faces are spaced apart with a casting 50 sandwiched therebetween and in which there is associated with each grooved plate an outer plate having end chambers whereby a fluid may flow in one or more passes through the outer grooves of one grooved plate and then 55 through the outer grooves of the other grooved plate in one or more passes.

9. A heat exchange apparatus as claimed in claim 1 comprising a pair of plates spaced 60 apart and each grooved in two opposite faces thereof, a casting interposed between said plates, a plate member provided with end chambers and located on the outer side of each grooved plate, and a pipe which bridges 65 the apparatus and is adapted to conduct a

fluid from a chamber of the one outer plate to a chamber of the other outer plate.

10. A heat exchange apparatus as claimed in claim 1 in which the ends of the channels are open to chambers located adjacent said ends whereby a fluid is caused to flow longitudinally through each set of channels in one or more passes.

In testimony whereof we have signed our names to this specification.

JOHN GRAVES McKEAN.
ROBERT FREDERICK JONES.
